UNITED STATES PATENT OFFICE.

CHARLES P. MOSHER, OF ROCHESTER, AND NELSON R. STREETER, OF GROTON, NEW YORK, ASSIGNORS TO THE ENTERPRISE MANUFACTURING COMPANY OF PENNSYLVANIA, OF PHILADELPHIA, PENNSYLVANIA.

DESIGN FOR A CLAMP ELEMENT.

SPECIFICATION forming part of Design No. 34,321, dated April 2, 1901.

Application filed March 13, 1899. Serial No. 708,957. Term of patent 14 years.

To all whom it may concern:

Be it known that we, CHARLES P. MOSHER, residing at Rochester, and NELSON R. STREETER, residing at Groton, New York, citizens of the United States, have invented and produced a certain new and original Design for a Clamp Element, of which the following is a specification.

Our design for a clamp element for attaching a food-cutter, food-press, fruit-seeder, or similar machine to a table or shelf is clearly illustrated in the accompanying drawings, in which—

Figure 1 is a perspective view of the clamp element. Fig. 2 is a front view, and Fig. 3 is a side view.

The essential feature of the design is the shape of the element shown.

A is the element, having two forwardly-extending arms *a a*, spread as shown, and connected at *b b'*, forming a slot *c*. The ends of the arms *a a* are ribbed, as shown.

We claim—

The design for a clamp element as herein described and as shown in the accompanying drawings.

In testimony whereof we have signed our names to this specification in the presence of two subscribing witnesses.

CHARLES P. MOSHER.
NELSON R. STREETER.

Witnesses:

E. PITCHER ALLEN,
N. A. MACPHERSON.
